UNITED STATES PATENT OFFICE.

JESSE W. VANIMAN, OF WICHITA, KANSAS.

STEAM-PLOW.

No. 853,046.

Specification of Letters Patent.

Patented May 7, 1907.

Application filed April 17, 1906. Serial No. 312,194.

To all whom it may concern.

Be it known that I, JESSE W. VANIMAN, a citizen of the United States, residing at Wichita, in the county of Sedgwick and 5 State of Kansas, have invented certain new and useful Improvements in Steam-Plows; and I do declare the following to be a full, clear, and exact description of the invention, such as will enable others skilled in the art to 10 to which it appertains to make and use the same.

This invention relates to steam plows, and one of the principal objects of the same is to provide a strong and durable frame for a 15 gang of plows, said frame adapted to lie close to the ground, so as to carry a supply water tank at an altitude that will admit of the gravity flow of water from the water wagon tank.

20 Another object of the invention is to provide a gang-plow with means for guiding the same by hand when the traction engine is moved backwardly.

A still further object of the invention is to 25 provide a caster-wheel, adapted to be operated by hand to guide the plow-frame when the engine is moving backward.

A further object of my invention is to provide a steam plow-frame with an angular 30 tube or bar for the attachment of any number of plows required.

These and other objects are attained by means of the construction illustrated in the accompanying drawings, in which,—

35 Figure 1 is a plan view of a steam plow made in accordance with my invention, and showing a portion of a traction engine to which the plow is attached; Fig. 2 is a side elevation of the plow detached from the traction engine; and Fig. 3 is a longitudinal section of a portion of the plow frame, and showing the caster-wheel and mechanism for operating it. Fig. 4 represents a side elevation of one of the tube supporting brackets.

40 Referring to the drawings for a more particular description of my invention, the frame of the plow, consists of a metal plate bent into substantially triangular or approximately V-shaped form and comprising the diagonally-extending portion, the laterally-extending portion 2, and the forwardly-extending portion 3 preferably of a length greater than the bar 1. Secured to the front ends of the frame members 1 and 2, by means 45 of bolts 4, is a combined water-tank and coal-bin 11, said coal-bin being provided with a

partition 12 shown in dotted lines in Fig. 2 to separate the lower compartment 13, for containing water, from the upper compartment 14, for containing coal. The front end of 60 this tank and bin is cut away to provide means for gaining ready access to the coal for the furnace of the traction engine. The plow is mounted upon front wheels 5, journaled to axles 6, said axles being bolted to 65 the side of the tank 11, as shown in Fig. 1. Secured to the frame are a series of brackets 7, said brackets each having a tubular portion for supporting a tube 8 which is disposed diagonally parallel with the frame member 1, 70 said tube having forwardly-extending, spaced lugs as 9, having their free ends bifurcated as at 9' between which plow standards not shown are adapted to be secured in any desirable manner.

75 A brace 10 is secured to the frame 1 by bolts 15, and extends forward, with its front end surrounding the tube 8, as shown in Fig. 1. Mounted in the frame of the plow in rear of the tank 11 is a caster-wheel 16 and mechanism for operating the same. The caster-wheel 16 is journaled in a frame 17, upon the front end of which a lug 18 is formed, said lug being pivotally connected between flanges 19, 20, on the caster-wheel frame. A flange 21 80 projects backward from the caster-wheel frame, and upon the upper side of said flange a ball-bearing raceway 22 is provided for antifriction balls 23, the balls being held underneath the lateral flange 24 of the vertical flange 24 to give sufficient room for the various movements of the caster-wheel frame upon its pivotal point. An opening through 85 the platform is made, said opening being substantially circular in form, as shown, and the flange 24 surrounds the opening. A cord, chain, or other flexible connection 25 is attached at opposite sides of the rear end of the 90 caster-wheel frame, said flexible connection passing around pulleys 25 mounted at opposite sides upon the flange 24, said flexible connection passing thence backward and around a drum 26, secured to a vertical shaft 27, upon the upper end of which a hand-wheel 28 is mounted for actuating the caster-wheel and directing the movement of the 95 plow-frame when running backward.

100 The draft attachment comprises a laterally-extending bar 29, secured to the front of the water tank support or frame of the plow, said bar being secured by brackets 30 to said frame and by a bracket 40 to the tube 8. A

draw-head 31 is secured by a pin 32 to the bar 29 and is adapted to be adjusted laterally in any of the perforations 33 to secure a central draft line under varying conditions. The 5 front end of the draw-head 31 is connected to the traction engine *a*. Draft chains 34, 35, are connected to the traction engine by suitable means and extend backward, cross each other, and are secured at suitable points to the laterally-extending bar 29. A bent bar 39 is connected at one end to the bar 29 and at its other end to the tube 8 with its intermediate portion connected with the axle 6. This draft appliance permits the traction 15 engine to turn in either direction freely, guiding the plow so that it will trail the engine.

Various changes in the form, proportion and the minor details of construction may be 20 resorted to without departing from the principle or sacrificing any of the advantages of this invention, as defined by the appended claims.

Having thus described my invention, what 25 I claim as new and desire to secure by Letters-Patent, is,—

1. A steam plow frame provided with a diagonally-disposed bar having lugs extending laterally therefrom with their free ends bifurcated to receive the plows and extended longitudinally of the frame.
2. A steam plow composed of a diagonally-

disposed bar having a short arm extending laterally therefrom, a bar extending at right angles from the free end of said arm, an annular member secured to the free end of the last-mentioned bar and to the diagonal bar, a smaller annular member secured between said bars, and a plow-carrying bar attached to said diagonal bar and extending parallel therewith.

3. A steam plow frame comprising an approximately V-shaped member having one arm shorter than the other and inclined, an annular member mounted between the free ends of said V-shaped member and secured thereto, land wheels connected with said annular member, a caster wheel mounted in the reduced end of said V-shaped member, spaced brackets secured to the short inclined arm of said V-shaped member, a diagonally-disposed bar mounted in said brackets and extended at each end beyond said V-shaped member, an arm connecting the long arm of said V-shaped member with said diagonal member and a plurality of plow receiving devices carried by said diagonal bar.

In testimony whereof I have hereunto set my hand in presence of two subscribing witnesses.

JESSE W. VANIMAN.
